BALL CASTER

Kenneth Charles Godard, South Croydon, England, assignor to C. W. Godard & Company Limited, South Croydon, England, a company of Great Britain

Application July 28, 1958, Serial No. 51,971

Claims priority, application Great Britain March 13, 1958

Term of patent 14 years

(Cl. D10—6)

Figure 1 is a side view of a ball caster showing my new design.

Figure 2 is an end view of the ball caster.

Figure 3 is a plan view of the ball caster.

Fig. 4 is a side elevation showing the side opposite to that shown in Fig. 1, and

Fig. 5 is an elevational view showing the end opposite to that shown in Fig. 2.

I claim:

The ornamental design for a ball caster, substantially as shown.
